R. C. SIMMONS,
PENCIL SHARPENING DEVICE,
APPLICATION FILED AUG. 30, 1916.

1,248,733.

Patented Dec. 4, 1917.

INVENTOR.

Ralph C. Simmons

BY Jas. H. Schenck

ATTORNEY.

UNITED STATES PATENT OFFICE.

RALPH C. SIMMONS, OF BEVERLY, MASSACHUSETTS.

PENCIL-SHARPENING DEVICE.

1,248,733.

Specification of Letters Patent. Patented Dec. 4, 1917.

Application filed August 30, 1916. Serial No. 117,571.

To all whom it may concern:

Be it known that I, RALPH C. SIMMONS, of Beverly, county of Essex, and State of Massachusetts, have invented an Improvement in Pencil-Sharpening Devices, of which the following description, in connection with the accompanying drawings, is a specification, like characters on the drawings representing like parts.

10 This invention relates to sharpening devices and is herein shown as embodied in a device for sharpening pencils.

The invention has for its object to provide a simple and efficient device for the purpose specified, and one in which the parts are easily accessible for adjustment or renewal. To this end I employ a conical cutter which is adjustably mounted on a post located within a shell or casing, and is locked 20 in its adjusted position on said post. The conical cutter has coöperating with it a guide for the pencil, preferably integral with an arm pivotally mounted on the post so that the guide is rotatable about the conical cutter.

25 The case or shell may and preferably will be provided with a cover, which is detachably connected with the guide arm, so as to revolve therewith and to be disconnected 30 therefrom, when it is desired to remove the chips from the case or shell or to gain access to the parts within the same. These and other features of this invention will be pointed out in the claims at the end of this 35 specification.

Figure 1 is a plan with the cover broken away of a pencil sharpener embodying this invention, and

Fig. 2, a vertical central section on the line 40 2—2 Fig. 1.

Referring to the drawing, *a* represents the shell or casing which is open at its upper end and closed at its lower end by the bottom *b*, provided with an upwardly extended 45 central hollow boss *c*. The parts of the case or shell may and preferably will be made in one piece of sheet metal, which serves to reduce the weight and cost of the apparatus.

The case or shell *a* has located within it a 50 conical cutter *d*, provided with exterior blades 10 and with a central bore 12 having screw threads 13, which are preferably located near the upper end of the bore and are engaged with screw threads 14 on the exterior of a post 15 near the upper end thereof.

The post 15 is made of a diameter equal to that of the hollow boss *c*, and is provided with a reduced lower portion 16 which fits into the hollow boss *c* and forms a shoulder 60 17, which rests upon the upper edge of said boss. The post 15 may be secured in the hollow boss *c* with a driving fit or in any other suitable manner, and may and preferably will be provided with an externally threaded 65 portion 18, which projects below the bottom of the case *a* and is engaged with a threaded socket 19 in a base plate 20, which may be provided with suitable holes 21 for the reception of screws 22, by means of 70 which the base plate may be firmly secured to a table, desk or other support 23. The post 15 is made of greater length than the conical cutter *d*, so that the latter can be adjusted axially on said post by turning the 75 cutter, and the latter may be locked in its adjusted position by a nut 25, which engages the screw threads 14 on the post and the upper end of the conical cutter.

The conical cutter *d* has coöperating with it a conical hollow guide 26 for the pencil 27 to be sharpened, said guide being attached to or integral with a rotatable support, herein shown as an arm 127, which is mounted on the reduced upper end 28 of a center pin 85 29, and rests upon the upper end of the post 15. The center pin 29 is extended into a cylindrical socket 30 in the post 15, and is made of material length to obtain a long bearing which prevents tipping or tilting 90 movement of the conical guide with relation to the conical cutter.

The case *a* may and preferably will be provided with a cover 31 provided with a center stud or pin 32, which fits into a socket 95 33 in the center pin 29, and said cover may be detachably connected with the guide carrying arm 127, by providing the cover with one or more holes 34 for the reception of a pin 35 carried by and projecting above 100 the arm 127. The conical guide 26 is provided with the same inclination as the conical cutter, and is provided with a slot 40 adjacent to the cutter for the pencil to project through and engage the said cutter. 105

In operation with the apparatus herein shown and described, the pencil 27 is inserted into the conical guide 26 through suitable openings 36 in the cover, and the latter and the guide are rotated by the operator 110 employing the pencil as a crank or handle. As the cover and guide are rotated, the pen-

cil is moved around the conical cutter in contact therewith until the pencil has been properly sharpened.

The conical cutter may be axially moved 5 on the post 15 to adjust the cutter with relation to the conical guide, by turning the cutter on the threaded portion 14 of said post, and when properly positioned, the cutter may be locked in its adjusted position 10 against axial movement on the post, by the nut 25, which is turned up on the threaded post until it engages the upper end of the conical cutter. Access may be had to the nut 25 and to the conical cutter, by slipping 15 the cover off of the holding or connecting pin 35, which can be done in a minimum time, and thereupon the nut 25 and cutter *d* are made accessible for adjustment or renewal of the cutter. Furthermore it will be 20 observed that the parts of the device are inexpensive to make, easy to assemble, and easy to adjust.

By providing the central bore of the conical cutter with screw threads and the 25 post 15 with external screw threads, the conical cutter may be made of minimum axial length and consequently of a minimum amount of metal, while obtaining the axial adjustment desired. The lower part of the 30 central bore of the conical cutter is preferably made larger than the diameter of the threaded portion of the post, to reduce the time required to engage the cutter with and remove it from the post.

35 It may be preferred to make the central post separate from the case, but it is not desired to limit the invention in this respect.

By adjusting the conical cutter on the post 15, the said cutter is adjusted with relation to the guide and the amount of material removed from the pencil on each revolution of the latter is thereby regulated.

Claims:

1. In a sharpening device of the character described, in combination, a case, a sub-

stantially central post located in said case and provided with screw threads on its exterior, a conical cutter having a bore provided with screw threads to engage the screw threads on said post and axially movable on said post, a nut on the threaded post coöoperating with the smaller end of the conical cutter to lock the latter in its adjusted position, a guide for the pencil, located in said case with its axis substantially parallel with the axis of said cutter and opposing the circumferential cutting surface of said cutter, and a support for said guide rotatable about said post as a center. 50 55

2. In a sharpening device of the character described, in combination, a case, a post located in said case, a conical cutter axially movable on said post, means for securing said conical cutter in fixed relation to said post, and a guide for the pencil opposing 60 the circumferential cutting surface of said cutter and movable about the conical cutter within said case in a path concentric with the axis of said cutter.

3. In a sharpening device of the character described, in combination, a case, a substantially central post located in said case and provided with screw-threads on its exterior and with a socket extended from its upper end, a conical cutter having a bore provided 70 75 with screw-threads to engage the screw-threads on said post and axially movable on said post, a nut on said threaded post co-operating with the smaller end of the conical cutter to lock the latter in its adjusted 80 position, a guide for the pencil coöperating with the circumferential cutting surface of said cutter, and a support for said guide provided with a center pin extended into the socket in the hollow post and revoluble 85 therein.

In testimony whereof, I have signed my name to this specification.

RALPH C. SIMMONS.
